UNITED STATES PATENT OFFICE.

WALTER MAECHLER, OF CHICAGO, ILLINOIS, ASSIGNOR TO LEE E. DANIELS, OF CHICAGO, ILLINOIS.

DESIGN FOR A MEAT-TENDERING IMPLEMENT.

55,481.

Specification for Design.

Patented June 15, 1920.

Application filed April 12, 1920. Serial No. 373,397. Term of patent 14 years.

To all whom it may concern:

Be it known that I, WALTER MAECHLER, a citizen of the United States, residing at Chicago, in the county of Cook and State of Illinois, have invented a new, original, and ornamental Design for a Meat-Tendering Implement, of which the following is a specification, reference being had to the accompanying drawing, forming a part hereof.

I claim:

The ornamental design for a meat-tendering implement, as shown.

W. MAECHLER.
